BOAT PROPELLING AND STEERING
MECHANISM

Fred S. Ball, Montgomery, Ala.

Application October 21, 1948, Serial No. 55,703

2 Claims. (Cl. 114—153)

1

Fishermen using rod and reel and who desire to work along shore and usually in shallow water require another person to handle and propel the boat. This is usually done with oars or paddle or by sculling. Devices have been proposed for propelling and steering the boat by the fisherman so as to dispense with a person whose purposes are to provide these operations. One of these proposed devices is a fin attached to the stern of the boat and movable by a laterally swinging arm, which arm oscillates the fin supporting shaft so as to propel as well as to steer the boat. Another solution of the problem is a slow speed outboard motor. In both instances, however, a hand of the fisherman is required to control the propelling and steering operations.

It is desirable to provide a combined propelling and steering mechanism for small boats which would enable the fisherman to have both hands free for his actual fishing activities, and it is the primary object of the present invention to provide means in combination with either of the above mentioned propelling and steering devices for bringing about steering and propelling operations of the boat without requiring the use of either or both hands of the fisherman, leaving the latter entirely free for the actual fishing activities.

A further object of the invention is to provide an attachment or mechanism for association with either or both of the propelling and steering means briefly mentioned which is of extremely simple construction, which may be readily connected with various types of propelling and steering mechanism for perfect operation of the latter, which means is capable of being quickly and easily attached to devices of the character set forth, which has its parts so constructed and assembled as to offer a minimum of opportunity for derangement or breakage of the same, which may be assembled or made operative by simple means and without the aid of special skill or knowledge, and which will prove highly practical and efficient in operation.

With the foregoing objects in view, together with others which will appear as the description proceeds, the invention consists in the novel construction, combination and arrangement of parts, all as will be described more fully hereinafter, illustrated in the drawings, and particularly pointed out in the claims.

In the drawings:

Fig. 1 is a perspective view of a conventional rowboat or skiff equipped with a foot operated propelling and steering means constructed in accordance with the invention.

2

Fig. 2 is a sectional view taken through the steering post or tiller and showing the manner of attachment of the steering cables thereto.

Fig. 3 is an enlarged side elevation of one of the stirrups or pedals,

Fig. 4 is a top plan view of the rear end of a conventional form of rowboat and showing as applied thereto an outboard electrically operated motor, associated with which is steering and motor control means involving my invention,

Fig. 5 is a detail view, parts in section, showing the means of connecting the steering and control cables with the tiller so as to bring about the steering and circuit control operations,

Fig. 6 is a plan view of a form of circuit control means, and

Fig. 7 is a side elevation, parts in section, of the pedal means and circuit control structure shown in Fig. 6.

20 Referring now more particularly to the drawing, the boat 10 as shown represents a small flat bottom skiff-type boat having the stern board 11 and a seat 12 spaced forwardly therefrom as usual. The steering and propelling device here illustrated and well known includes a bracket 13 to be engaged upon the stern of the boat and having vertically aligned bearings 14 in which a shaft 15 is mounted for oscillation. The oscillatory movements of this shaft are governed by a lever 16 affixed to the upper end of the shaft 15 and having a hand grip 17 disposed within convenient reach of an occupant of the seat 12. The lower end of the shaft is bent rearwardly and at right angles as shown and is equipped at its rear end with a fin 18 to propel as well as to steer the boat. The construction and mounting of the fin upon the shaft 15 is such that as the shaft oscillates the fin provides a thrust in the body of the water to move the boat forwardly. It is obvious, also, that oscillations 30 of the shaft bring about a steering operation.

The attachment of my invention includes a pair of pedals indicated at 19. The pedal members are preferably flat as shown and are adapted to fit beneath the ball of the foot, each pedal 45 being equipped with a strap and buckle 20 as shown to engage over the forward part of the foot so that the pedal, in effect, provides a stirrup for easy attachment to or removal from the foot.

50 Each of these pedals or stirrups is connected by means of ropes or light cables 21 to the operating arm 16 of the propelling and steering device. To this end, each strap has an eye 22 secured thereto and through which one end of the cable 55 or rope 21 is attached. The rope or cable from

each stirrup passes rearwardly to the stern of the boat and around pulleys 23 secured as at 24 to the sides of the boat, from whence they extend inwardly and laterally of the boat and are secured to the horizontally disposed and forwardly projecting operating arm 16. To facilitate the attachment of these cables or rope to the arm, a clamp 25 is detachably secured to the arm, which clamp is provided with eyes 26 through which the ends of the cables or ropes are passed and tightly secured. The clamp is shown more in detail in Fig. 2 and discloses a wing nut and bolt 27 for securing the arms of the clamp in tight engagement with the steering and propelling arm. The construction shown permits the clamp to be easily and quickly attached to the arm or removed therefrom.

In operation, with the attachment applied in the manner shown in Fig. 1, the occupant of the seat 12 applies the stirrups to his feet in the obvious manner. The cables or ropes 21 are adjusted as to proper length. By alternately pushing upon the pedals or stirrups the arm 16 is caused to move from side to side creating oscillatory movement in the shaft 15 and bringing about a propulsion of the boat. The movement of the feet alternately may be brought about by rocking on the heel which rests upon the boat bottom. This propelling action is created without the use of the hands so that the fisherman may employ the latter for his actual fishing activities. In order to bring about a steering action, one foot is pressed further forward than the other in the backward and forward movement and the fin, although being worked from side to side to propel the boat, works off-center so as to cause the boat to steer in the direction desired by the operator. It is apparent that the construction disclosed permits of the boat to be propelled at a desired speed and its directional movements accurately controlled. The construction of the stirrups is such that they may be readily detached from the feet when occasion demands, and equally as quickly applied thereto.

It is preferred that the strap be so adjusted that the stirrup will be held upon the outer part of the foot so as not to slip down beyond the forward part of the ball, whereby the greater arc of movement in rocking the foot is made possible. The clamp means here shown for connecting the rear ends of the ropes or cables with the steering arm may be dispensed with if desired and other means be resorted to for bringing about an attachment of these elements to the tiller. If desired, openings may be drilled in the arm to receive the ends of the ropes or cables.

As has been before stated, the invention includes foot actuated means whereby the starting and stopping of an outboard motor may be accomplished as well as the steering actions of the motor. In Fig. 4 of the drawings there is illustrated a plan view of the rear portion of a conventional fishing skiff, to the stern of which is attached an electrically operated outboard motor represented generally at 30, including a tiller 31 to be operated by oscillatory movement for steering. The battery to supply the electric energy for operation of the motor is indicated at 32, one terminal of which is connected by a wire 33 to one side of the motor. The cables 21, pulled or retracted by operation of the feet, pass over the pulleys 23 in the rear corners of the boat and have quick detachable devices, such as snap hooks 34 connected to their ends. These snap hooks connect to rings 35 secured to slide contact members 36 within insulating members 37 secured in

the outer end of a yoke 38. The inner end of each of these slide rods or contact members is provided with an eye 39 to which one end of contractile spring 40 is attached, the opposite end 5 of the spring being connected to the screw eye 41 in the opposite end of the yoke. The screw eye 41 has a snap hook 42 attached thereto for engagement with the eye 26 of the clamp member 25 engaging the tiller 31.

10 The opposite terminal of the battery 32 is connected to each of the ring members 35 by a wire 43, and each of the yokes 38 is connected to the opposite side of the motor 30 by a wire 44.

15 The inner end of each of the slide rods 36 is equipped with a contact plate 45 which is normally out of contact with its respective yoke 38 by reason of the action of spring 40, but upon outward sliding movement of rods 36 these contact plates engage yokes 38 to close a circuit from 20 one terminal of the battery 32 through the motor 30 by means of wire 33 and back through wire 44, yoke 38, rod 36, ring 35 and wire 43 to the opposite battery terminal.

25 In the operation of this form of control, movement of a pedal forwardly will draw upon its cable to swing the tiller 31 and at the same time to close the circuit through the motor and battery whereby the motor is energized. Release of pressure upon the stirrup or pedal enables the spring 40 to move the contact plate 45 to broken circuit position, whereupon the motor ceases operation. It is apparent that by providing circuit controlled 30 mechanism for each of the cables 21, accurate steering and propulsion of the motor is accomplished.

35 In Figs. 6 and 7 of the drawing, there is illustrated a modified form of electric control. In this form of the invention a battery supporting base 50 is employed, which base may be of wood and of approximately the size and shape of the usual storage batteries for motors of the character here under consideration. The battery, indicated at 51, rests upon this plate so as to maintain it in proper position in the bottom of the boat. Hingedly connected to a strip 52 secured to the rear of plate 50 and transversely thereof, are pedals 53 having heel rests 54 near the hinge connections 55 thereof. A control cable 21 is secured near the free end of each pedal.

40 Each pedal is provided with a leaf spring contact member 56, to one end of which is secured a wire 57 leading to the battery 51, while the outer or free end thereof is adapted to engage a contact member 58 carried by the pedal and 45 electrically connected by a wire 59 to the motor. The leaf spring 56 is so positioned that under normal conditions the feet may operate the hinged pedals to bring about a steering action in the motor, however, upon slightly rocking the 50 foot of either pedal to depress the spring 56 until it engages contact member 58, a circuit is closed through the motor and battery whereby the former is energized. Release of this 55 rocking pressure immediately permits leaf spring contact 56 to resume its normal position breaking the circuit.

60 From the foregoing, it is apparent that I have provided means of extremely simple construction and operation for bringing about propulsion of a small boat by operation of the feet and without requiring the use of the hands. By the means described, accurate steering of the boat is readily accomplished. It is also apparent that by use of either of the circuit controlling 65 means described, actuation of the outboard

motor may be accurately governed as may also the steering operations thereof.

While the foregoing is a description of the invention in its preferred embodiment, it is obvious that various changes in the details of construction and assemblage may be resorted to without departing from the spirit of the invention as defined by the claims.

I claim:

1. In combination, a motor, a source of energy and an electric circuit including said motor and source and an oscillatory tiller connected to said motor to move the same; a movable stirrup, a yoke connected at one end to said tiller, a slide pin movable longitudinally within said yoke and projecting beyond the opposite end of said yoke, a contact plate on said pin, means within said yoke tending to hold said plate out of contact with said yoke, a cable connecting the outer end of said pin with said stirrup, and said circuit including said yoke and said contact pin, whereby movement of the stirrup in one direction will cause said contact plate to move into contact with said yoke and to simultaneously move said tiller.

2. In combination, a motor, a source of energy and an electric circuit including said motor and source and an oscillatory tiller connected to said motor to move the same; a pair of movable stirrups, a pair of yokes one arranged upon each side of said tiller and connected at its adjacent end to said tiller, a pin slidable longitudinally

within each of said yokes and projecting beyond the outer ends thereof, a contact plate on each of said pins, a spring within each yoke tending to hold said plate out of contact with said yoke when said tiller is in one position, a pair of cables each connected at one end to the outer ends of said pins and at their opposite ends with one each of said stirrups, and said circuit including said yoke and said contact pin, whereby movement of either stirrup in a predetermined direction will move said tiller and will simultaneously cause its contact plate to move into contact with its respective yoke.
